United States Patent Office

Des. 198,591
Patented July 7, 1964

198,591

BOTTLE CARRYING CASE

Karl Brocken, 195 N. Farnsworth, Aurora, Ill.

Filed Dec. 20, 1963, Ser. No. 77,879

Term of patent 3½ years

(CL D58—5)

FIG. 1.

FIG. 2.

FIG. 3.

FIG. 4.

FIG. 1 is a perspective view of a bottle carrying case showing my new design;

FIG. 2 is a top plan view thereof;

FIG. 3 is a bottom plan view thereof; and

FIG. 4 is an elevational view of one end thereof, the other end being a mirror image of the one shown.

I claim:

The ornamental design for a bottle carrying case, substantially as shown and described.
